United States Patent Office

Des. 195,703
Patented July 16, 1963

195,703

PRINTER CONSOLE

Frank Wilkey, Jr., Johnson City, N.Y., assignor to International Business Machines Corporation, New York, N.Y., a corporation of New York

Filed Sept. 6, 1960, Ser. No. 62,139

Term of patent 14 years

(Cl. D64—11)

FIG. 1

Des. 195,703

PAGE 2

FIG. 3

FIG. 1 is a front perspective view of a printer console showing my new design;

FIG. 2 is a rear perspective view thereof on a slightly larger scale; and

FIG. 3 is a side elevational view thereof.

I claim:

The ornamental design for a printer console, as shown.
